PICKING MECHANISM FOR LOOMS

Theodore F. Rapp, Delmar, and Robert J. Demartini, Rensselaer, N. Y., assignors to F. C. Huyck & Sons, Rensselaer, N. Y., a corporation of New York

Application June 24, 1954, Serial No. 439,044

15 Claims. (Cl. 139—142)

This invention relates to looms and more particularly to a picking motion admirably suited for use in extremely wide looms of the type employed in the weaving of paper-makers felts, carpets and similar fabrics.

In U. S. Letters Patent 1,966,704 granted July 17, 1934 and Patent 2,517,454 granted August 1, 1950 to Van Alstyne et al., there is disclosed picking mechanism in which the energy in a rotating flywheel is availed of for pulling the picker straps which are attached to the picker means, which in said patents are picker sticks. A mechanical clutch device is provided between the rotating flywheel and the picker sticks. A particular feature of Patent 2,517,454 is the provision of adjusting means for varying the interval during which the clutch elements are held in engagement. The latter patent also provides adjustable means for varying the pressure with which the clutch elements are forced into or held in engagement. The adjustable features thus provided make it possible to select the desired strength and duration of the picking stroke for any particular set of circumstances. However, such adjustments may be made only when the loom is stopped. Thus, several starts and stops might have to be made before suitable picking action is achieved. Furthermore, with apparatus such as that shown in the Van Alstyne et al. patents aforesaid, every pick from a particular end of the loom will be of approximately the same strength.

It is an object of the present invention to provide picking mechanism in which the energy in a rotating flywheel is availed of for moving the picker means and in which the strength of pick is consistently uniform when desired and yet may be varied while the loom is in operation. By providing independent mechanism at the opposite ends of the loom the relative strength of picks from opposite ends may be made equal or unequal as desired. Furthermore, the present invention makes it possible to automatically provide picks of different strength from either or both ends of the loom in accordance with shedding conditions.

The present invention provides, for achieving the objects thereof, an electro-magnetic clutch between the rotating flywheel and the picker means with adjustable timing devices for engaging and disengaging the clutch in proper timed relation with the other operations of the loom. Also, there may be provided adjustable means for varying the force with which the clutch elements are engaged whereby the strength of pick may be varied either manually for over all adjustment of pick strength or automatically to produce picks of greater or less strength in accordance with shedding conditions.

Other and further objects of this invention will vary from a consideration of the following detailed disclosure or preferred, but not necessarily the only forms of the invention, taken in connection with the drawings forming a part of this specification.

In the drawings:

Fig. 1 is a front elevational view of a loom embodying the present invention;

2

Fig. 2 is a wiring diagram;

Fig. 3 is a section along the line 3—3 in Fig. 1;

Fig. 4 is an elevational view from the right hand end of Fig. 3;

Fig. 5 is a plan view of the parts shown in Fig. 3;

Fig. 6 is a fragmentary view of certain parts at the extreme right hand end of the loom shown in Fig. 1;

Fig. 7 is a vertical section along the line 7—7 in Fig. 6;

Fig. 8 is a vertical section along the line 8—8 in Fig. 6;

Fig. 9 is a wiring diagram similar to Fig. 2 but showing a modified form of the invention; and

Fig. 10 is a view similar to Fig. 6, showing one form of switching arrangements suitable for use in connection with the modification illustrated in Fig. 9.

Referring now to Fig. 1, there is shown a loom indicated generally at 10 which includes a head motion indicated generally at 12, a head end shuttle box 14 and drive end shuttle box 16 and a main drive shaft 18 which performs one complete revolution on each pick. The parts thus far identified may be of any conventional form depending upon the particular loom to which it may be desired to adapt the present invention.

At the head end of the loom there is provided a picker stick 20 adapted to propel a shuttle (not shown) from any of the cells of the head end shuttle box 14 upon movement of the picker stick in a clockwise direction as viewed in Fig. 1. At the drive end of the loom a picker stick 22 is provided for cooperation with shuttles in the drive end shuttle box 16 and which is adapted to propel a shuttle from the box 16 upon movement of the picker stick 22 in a counterclockwise direction as viewed in Fig. 1. The picker sticks 20 and 22 are each provided with a return spring 24 and 26, respectively, which serves to return the picker sticks to the position shown in Fig. 1 by exerting tension upon straps 28 and 30 attached respectively to the lower ends of the sticks 20 and 22. Each of the picker sticks 20 and 22 are connected through picker straps 32 and 34, respectively, with clutches indicated generally at 36 and 38 which incorporate flywheels which will be described hereinbelow and which are driven by motors 40 and 42 through belts 44 and 46.

Referring now to Figs. 3 and 4 wherein for purposes of illustration the clutch 38 is shown in detail, it will be observed that the mechanism is supported in a stand comprising spaced vertically extending members 48 and 50 and a horizontally disposed channel member 52. A horizontally disposed shaft 54 is fixed at its opposite ends against rotation to the vertical frame members 48 and 50. A flywheel 56 is mounted for rotation upon the shaft 54 by means of suitable bearings 58. The flywheel 56 is provided with a V-shaped groove 60 to receive the belt 46 which connects the flywheel 56 with the motor 42. A hub 62 is secured as by cap screws 64 to the flywheel 56.

The driving member 66 of an electrical clutch is secured through a ring 68 to the hub 62. Thus the driving member 66 rotates with the flywheel 56 about the fixed shaft 54. The hub 62 carries on its periphery a ring 70 made of electrically non-conductive material and having embedded therein slip rings 72 and 74 made of electrically conductive material. The slip rings 72 and 74 are electrically connected with opposite ends of a winding 76 positioned within the clutch driving member 66. Brushes 78 and 80 (each actually comprising two brush elements as shown in Fig. 4) are arranged to establish electrical contact respectively with the slip rings 72 and 74. The brushes 78 and 80 are carried in a brush holder indicated generally at 82 which is supported by a stationary frame member 84 secured at its lower ends to the channel 52. Wires 86 and 88 extend from the brush holder 82 for

establishing desired connection with the brushes 78 and 80.

The driven member of the clutch 38 includes a hub 90 freely rotatable and axially slideable upon the fixed shaft 54 by means of suitable bearings 92. A thrust washer 94 is positioned in a suitable recess in the hub 90 and is arranged to engage an adjustable nut 96 to limit longitudinal movement of the hub 90 in one direction. An expansive coil spring 98 extends between a collar 100 fixed upon the shaft 54 and a thrust bearing 102 disposed against the hub 90. The spring 98 thus urges the hub 90 to move longitudinally of the shaft 54, yieldingly urging the thrust washer 94 into engagement with the nut 96. The hub 90 carries a clutch face assembly which may be secured to the hub 90 by a plurality of bolts 104. The clutch face assembly may be of any suitable commercial form, the form illustrated comprising a retaining disk 106 having ventilating louvres 108 and arranged to support a generally ring-like clutch element 110 made of a ferrous metal capable of being attracted magnetically. As indicated above, the precise structure of the clutch elements is immaterial to the present invention. For example, the ring-like clutch element 110 actually may comprise a series of circumferentially disposed iron shoes and the retaining disk 106 is so constructed as to provide for minute relative movement between the shoes to insure intimate contact therewith of the face of the electromagnet 66.

The position of the parts illustrated in Fig. 3 is that which exists when the clutch elements are disengaged, being held in disengaged position by the spring 98. The spacing between the disengaged elements of the clutch 38 may be adjusted by appropriate positioning of the nut 96. To this end the nut 96 is threadably received upon a sleeve 112 fixed upon the shaft 54. Preferably, the nut 96 is provided with a set screw 114 to maintain the same in adjusted position. Upon energization of the coil 76 of the driving member 66 the ring-like member 110 is attracted into engagement with the driving member 66 and the hub 90 moves longitudinally of the shaft 54 against the spring 98 whereupon rotation will be imparted to the hub 90.

Rotation thus imparted to the hub 90 is transmitted to the picker sticks through the following mechanism. The hub 90 is provided with a lug 116 having an opening 118 therein to receive the picker strap 34. The picker strap 34 has secured on the end thereof a fitting 120 which is larger than the opening 118 and thus serves to anchor the end of the picker strap 34 to the lug 116. The hub 90 is also provided with a surface 122 extending away from the lug 116 and having a constantly increasing radius of curvature. The surface 122 is aligned with the picker strap 34 so that upon rotation of the hub 90 in a counter-clockwise direction, as viewed in Fig. 4, the strap 34 will wind upon the surface 122. The constantly increasing radius of curvature of the surface 122 will accelerate the rate of winding and longitudinal movement of the strap 34. Such action provides desired accelerated movement of the picker stick 22 for propelling a shuttle across the loom. It will be apparent that only a fraction of a revolution of the hub 90 is required for complete operation of the picker stick 22. Thus the clutch elements described above must be disengaged at the proper time to permit the hub 90 to cease rotation when sufficient movement has been imparted to the picker stick 22. The present invention provides suitable electrical timing means for deenergizing the electromagnet in clutch 38 to secure this result.

Upon deenergization of the electro-magnetic clutch 38 the return spring 26, through strap 30, will be effective to swing the picker stick clockwise as viewed in Fig. 1 and thus to unwind the picker strap 34 from the hub 90. The hub 90 is provided with a stop lug 124 which engages the fixed stop 126 carried by a bracket 128 mounted upon the frame member 52.

From a consideration of the description so far presented, it will be apparent that while the picker stick 22 will always return to a fixed position determined by the stop members 124 and 126, the length of the stroke in an active direction may be varied by the operating of timing means which will serve to deenergize the electromagnet. The strength of the stroke of picker stick 22 is dependent upon the ultimate speed and duration of the accelerated rotation of the hub 90 during the time that the strap 34 is being wound thereupon. Therefore a primary selection of strength of pick may be made by selection of speed of rotation of the flywheel 56 and by the timing of deenergization of the clutch magnet. Beyond this, however, the present invention provides means for varying the strength of pick by varying the flux density of the magnetic field established upon energization of the winding 76. A simple way of achieving this result is illustrated herein and consists essentially in the provision of a variable resistance in the circuit through which winding 76 is energized. As the amount of resistance inserted in the circuit increases the flux density will decrease and the driving element of the clutch 38 will be less positively engaged by the driven element. The less positively such engagement occurs, the more slippage will result between the driving and driven elements of the clutch 38 and the rate of acceleration as well as the ultimate speed of the picker stick 22 will be correspondingly reduced. In Fig. 2 there is shown a suitable circuit diagram for adapting the present invention to a loom with provision for proper timing and for the selection of suitable pick strength at each end of the loom while the same is in operation if so desired. In Fig. 9 there is illustrated a modified circuit diagram for achieving all of the functions provided in Fig. 2 and, in addition, providing for automatic variation in pick strength in accordance with shedding conditions.

Referring first to Fig. 2, lines 130, 132 and 134 may be connected with a source of three-phase alternating current. A switch 136 is connected through lines 138, 140 and 142 and may be closed to energize the motors 40 and 42. A single phase circuit consisting of the lines 142 and 140 is simultaneously energized to close a magnetic switch 144. The switch 144 is interposed in a line 146 which, with a line 148, is connected with a source of single-phase alternating current. In a typical installation the three-phase circuit for energizing the motors 40 and 42 may be at 460 volts and the single-phase circuit controlled by the magnetic switch 144 may be at 115 volts. The 115-volt line 146 may be connected by magnetic switch 144 through a line 150 and fuse 152 with one input side of a full wave rectifier indicated generally at 154. The line 148 is connected to the opposite side of the rectifier 154. The rectifier 154 has been provided to supply direct current to the electromagnets in the clutches 36 and 38. It will be understood that alternating current might be used for energizing magnets of suitable design if available to the user, in which event the circuit and related apparatus would be appropriately altered. Obviously, the selection of suitable voltages and current sources are matters of individual choice and form no limitation upon the present invention.

In the form of invention shown in Fig. 2, the winding 76 for the drive end clutch 38 is connected through wires 75 and 77, slip rings 72 and 74 and associated brushes 78 and 80, with positive and negative outputs of the rectifier 154. The negative side is connected through a line 156 and line 86 while the positive side is connected through a cut-off ring 158, a variable resistor 160, a selector switch indicated generally at 162 and a timer switch indicated generally at 164.

The selector switch 162, in its simplest form, may include a fixed contact 166, another fixed contact 168 and a pivoted contact arm 170 adapted to be selectively engaged with one or the other of the fixed contacts 166 or 168. In the position shown in Fig. 2, the arm 170

engages the contact 168 for energizing the winding 76 of the drive-end clutch 38. The fixed contact 166 is connected through a line 172, a variable resistor 174, similar to the resistor 160, a cut-off ring 176 and a slip ring 178 with the winding 180 for the head-end clutch 36. The opposite end of the winding 180 is connected through a slip ring 182 with the negative line 156. Thus when the arm 170 of selector switch 162 engages the contact 166 the head-end clutch winding 180 will be energized and the drive-end clutch winding 76 will not be energized. As shown in Fig. 1, the selector switch 162 may be positioned at the head-end of the loom and adapted for operation by a suitable part of the head motion to determine the end of the loom from which a pick is to occur.

The timer switch 164, in its simplest form, may comprise a fixed contact 184, and a pivoted contact arm 186 having a cam follower 188 bearing upon a cam 190 having a flat 192. Rotation of the cam 190 to bring the flat 192 into engagement with the cam follower 188 will result in closing of the contacts 186 and 184 whereas in all other positions of the cam 190 said contacts will be open as illustrated in Fig. 2. As shown in Fig. 6, the timer switch 164 may be mounted upon the frame of the loom near the drive end thereof and arranged to close the contacts 186 and 184 for a brief period during each cycle of the loom.

Mechanical details of one illustrative form of timer switch 164 and selector switch 162 will be set forth hereinbelow although it will be understood that either or both of these switches may take many forms and may be operated by any of a number of the moving parts of the loom.

The cut-off ring 158 for the drive end clutch 38 may be mounted as shown in Figs. 3 and 4, for example, and the mechanical details thereof will be set forth hereinbelow. However, for the purposes of understanding the circuit diagram in Fig. 2, it is sufficient to state that the cut-off ring 158 is made of electrically conductive material and describes less than a complete circle and is mounted upon the driven element of the clutch for rotation therewith. As shown in Fig. 2, the cut-off ring 158 is provided with a brush 194 which remains constantly in engagement therewith and an arcuately adjustable brush 196 which is in contact with the cut-off ring 158 when the clutch is in the disengaged position. Upon energization of the clutch 38 the cut-off ring 158 will rotate with the driven member in a counter-clockwise direction as viewed in Fig. 2, eventually to bring the open segment of cut-off ring 158 opposite the adjustable brush 196. When this occurs the winding 76 is deenergized. It will be apparent that the timer switch 164 is relied upon to initiate energization of the clutch and that the cut-off ring 158 is relied upon for deenergizing the clutch. The arcuately adjustable brush is provided in order that precise timing of the cut-off may be achieved. A condenser 198 may be connected between the brush 196 and the negative line 156 in order to suppress arcing when the circuit is opened as described.

Referring now particularly to Figs. 6, 7 and 8, an illustrative form of timer switch is shown. The switch 164 may be positioned within a casing 200 and have projecting therefrom a rotatable shaft 202. The shaft 202 may be internally connected with or have formed thereon the cam 190 described hereinabove and the contacts 184 and 186 may be connected into the circuit by means of a cable 204 projecting from the case 200. Illustratively, the timer switch 164 may be mounted on the frame of the loom adjacent the main drive shaft 18 and may be connected with such shaft by sprockets 206 and 208 and a sprocket chain 210. The sprockets 206 and 208 may be of the same diameter whereby to cause closing of the contacts 184 and 186 once for each revolution of the shaft 18. Preferably also, the casing 200 of the switch 164 is secured within a clamp ring 212 fixed upon the

loom frame whereby the casing 200 may be secured in a desired rotated position to bring about closing of the contacts at the precise instant required for initiation of the picking operation. As a matter of convenience, 5 index marks 214 may be provided on the switch casing 200 for cooperation with a suitable fixed index mark 216 to indicate the relative position of the timer switch.

The selector switch 162, as stated above, may be operated in any convenient manner from the head motion 10 of the loom. As shown illustratively in Fig. 1, the selector switch 162 may be provided with an actuating lever 218 connected by a link 220 with a shift lever 222 normally provided in the loom for actuating the pick motion which has been supplanted in the present invention by the 15 mechanism described above. The lever 222 swings between two different positions in response to a pattern chain 224, all as well understood in this art. The motions of the shift lever 222 may be transmitted through the link 220 and actuating arm 218 to place the swinging 20 contact arm (see Fig. 2) selectively in engagement with the contacts 166 and 168.

As shown in Figs. 3, 4 and 5, the cut-off ring 158 may be carried on the outer periphery of a housing 226 secured by screws 228 to the hub 90. The cut-off ring 158 is electrically insulated from the housing 226 by a ring 230 of insulating material in which the cut-off ring 158 is embedded whereby to present a smooth periphery partially conductive and partially non-conductive for engagement by the adjustable brush 196. The adjustable brush 196 may be carried by an arm 232 upon a collar 234 which conveniently may form a part of the threaded sleeve 112 upon which the nut 96 is carried. The collar 234 is provided with set screws 236 for holding the same fixed against the shaft 54. It will be apparent that 35 the brush 196 thus may be arcuately adjusted relative to the cut-off ring 158 and held in such position by the set screws 236. As pointed out above, such adjustment of the brush 196 establishes the precise moment for de-energization of the electro-magnet within the clutch 38. 40 The fixed brush 194 may be carried by a bracket 238 secured by screws 240 to the clamp 242 within which the shaft 54 is fixed.

The flux density of the electro-magnets may be controlled by the variable resistor 60 for the drive end clutch 38 or the variable resistor 174 for the head end clutch 36. The control knobs for these variable resistors have not been shown in the drawings and it will be understood that such knobs as well as various other controls may be embodied in an instrument panel conveniently accessible to 50 the operator of the loom.

The operation of the device so far described has been brought out in the course of the description of the various parts thereof. The primary advantages offered by said Patents 1,966,704 and 2,517,454 have been retained and 55 the provision of the electro-magnetic clutch provides not only a more consistent pick strength but also the very great further advantage of the control of timing and pick strength while the loom is in operation. The timer switch 164, the cut-off brush 196 and the variable resistors 160 and 176 all may be operated while the loom is active.

As stated above, the particular construction of the electrical clutch forms no part of the present invention inasmuch as suitable units are available in the market from several sources. It should be pointed out, however, 65 that many such clutches incorporate the electro-magnetic windings in the driven member whereas in the present instance it is preferable to incorporate such windings in the driving member. This not only avoids application of shock loads to the windings but also reduces the inertia of the driven member. Inasmuch as energy is stored in a flywheel rotating with the driving member in the present construction the additional mass represented by the relatively heavy windings is advantageous.

It will be understood that the head-end clutch 36 may 75 be identical with the drive end clutch 38 described here-

inabove in detail. Therefore, except for such elements as have been described in connection with the circuit diagram in Fig. 2, it has not been regarded as necessary to describe all of the elements of the clutch 36.

In Figs. 9 and 10 there is illustrated a modification of the invention which incorporates all of the features described above in connection with Figs. 1 through 8 and in addition shows one illustrative form of automatic control of pick strength. The circuit diagram presented in Fig. 9 is thus identical with that in Fig. 2 except that provision is made for placing a shunt across the variable resistors 160 and 174 at any time when a stronger pick is desired. Thus, in Fig. 9 a shunt resistor 244 is connected through a line 246 with one side of the variable resistor 160 and through a switch 248 and line 250 with the other side thereof. The switch 248 may be identical in construction with timer switch 164 described hereinabove whereby upon each revolution of a cam 252 therein a movable contact 254 is brought into engagement with a fixed contact 256 thereby placing the shunt resistor 244 across the variable resistor 160. Similarly, a shunt resistor 258 and switch 260 is provided for the variable resistor 174. The switch 260 may be provided with a cam 262 adapted upon each rotation to close the circuit including the shunt resistor 258.

As shown in Fig. 10, the shaft 202 of the timer switch 164 may be extended to accommodate a sprocket 264 connected by a sprocket chain 266 and sprocket 268 with a shaft 270 upon which is also carried a sprocket 272. The sprocket 272 is connected through a sprocket chain 274 with another shaft 276. The shafts 270 and 276 extend into change-gear boxes 278 and 280, respectively, secured upon the frame of the loom. The shafts 270 and 276 constitute input shafts for said change-gear boxes 278 and 280 and the output shafts thereof are connected respectively with the switches 248 and 260. It will be understood that appropriate gearing will be arranged within the change-gear boxes 278 and 280 to provide any desired ratio between the input shafts 270 and 276 and the rotary elements of the switches 248 and 260. In certain types of weaving the shed formed for one pick may offer a predetermined resistance to the flight of the shuttle whereas the shed formed for the next pick may offer very much greater or very much less resistance. This becomes important, for example, in Wilton-type carpet looms in which loop-forming wires lay in the warpwise direction. By the selection of appropriate gear ratios for the boxes 278 and 280, the switches 248 and 260 may be caused to close at regular intervals corresponding with the demand for stronger picks.

The mechanism just described is merely illustrative and it will be understood that the principles of the present invention are not limited to looms in which the picking means is in the form of the conventional picking sticks herein illustrated. Also, it will be readily understood that switches for controlling the strength of pick may be incorporated in the head motion, for example. In such event switches substantially identical with the selector switch 162 described hereinabove may be connected with appropriate levers in the head motion to bring about a stronger pick when some specific shedding condition is established. Obviously, also, the shunt resistors 244 and 258 illustrated herein may be variable resistors similar to the resistors 160 and 174 whereby to establish desired strength of the stronger picks.

We claim:

1. In a picking mechanism for looms having picker means at each end thereof, actuating mechanism for each picker means comprising a rotatable driving clutch element, means for rotating said driving clutch element, a driven clutch element, means including an electro-magnet adapted upon energization of said electro-magnet to drivingly engage said driving and driven clutch elements, means for moving said driving and driven elements into disengaged position upon deenergization of said electro-

magnet, means actuated by said driven element for imparting motion of said driven element to the associated picker means, switch means operated by said loom for energizing said electro-magnet in proper timed relation for initiation of movement of the associated picker means, and switch means operated by said driven clutch element for deenergizing said electro-magnet.

2. In a picking mechanism for looms having picker means at each end thereof, actuating mechanism for each picker means comprising a flywheel, means for rotating said flywheel, a driving clutch element fixed for rotation with said flywheel, a driven clutch element, means including an electro-magnet adapted upon energization of said electro-magnet to drivingly engage said driving and driven clutch elements, means for moving said driving and driven elements into disengaged position upon deenergization of said electro-magnet, means actuated by said driven element for imparting motion of said driven element to the associated picker means, switch means operated by said loom for energizing said electro-magnet in proper timed relation for initiation of movement of the associated picker means, and switch means operated by said driven clutch element for deenergizing said electro-magnet.

3. In a picking mechanism for looms having picker means at each end thereof, actuating mechanism for each picker means comprising a rotatable driving clutch element, means for rotating said driving clutch element, a driven clutch element, means including an electro-magnet adapted upon energization of said electro-magnet to drivingly engage said driving and driven clutch elements, means for moving said driving and driven elements into disengaged position upon deenergization of said electro-magnet, means actuated by said driven element for imparting motion of said driven element to the associated picker means, and electrical control means operated by said loom for selectively energizing and deenergizing the electro-magnet in one or the other of said actuating mechanisms during each pick cycle of the loom, said electrical control means including means operable while said loom is in operation for varying the times in each pick cycle at which the selected electro-magnet is energized and deenergized.

4. In a picking mechanism for looms having picker means at each end thereof, actuating mechanism for each picker means comprising a rotatable driving clutch element, means for rotating said driving clutch element, a driven clutch element, means including an electro-magnet adapted upon energization of said electro-magnet to drivingly engage said driving and driven clutch elements, means for moving said driving and driven elements into disengaged position upon deenergization of said electro-magnet, means actuated by said driven element for imparting motion of said driven element to the associated picker means, switch means operated by said loom for energizing one or the other of the electro-magnets in said actuating mechanism during each pick cycle of the loom for initiating of movement of the associated picker means, switch means operated by the affected driven clutch element for deenergizing the affected electro-magnet, and means operable while said loom is in operation to independently vary the times at which each of said switch means is effective.

5. In a picking mechanism for looms having picker means at each end thereof, actuating mechanism for each picker means comprising a flywheel, means for rotating said flywheel, a driving clutch element fixed for rotation with said flywheel, a driven clutch element, means including an electro-magnet adapted upon energization of said electro-magnet to drivingly engage said driving and driven clutch elements, means for moving said driving and driven elements into disengaged position upon deenergization of said electro-magnet, means actuated by said driven element for imparting motion of said driven element to the associated picker means, switch

means operated by said loom for energizing one or the other of the electro-magnets in said actuating mechanisms during each pick cycle of the loom for initiation of movement of the associated picker means, switch means operated by the affected driven clutch element for deenergizing the affected electro-magnet, and means operable while said loom is in operation to independently vary the times at which each of said switch means is effective.

6. In a picking mechanism for looms having picker means at each end thereof, actuating mechanism for each picker means comprising a rotatable driving clutch element, means for rotating said driving clutch element, a driven clutch element, one of said clutch elements including an electro-magnet and the other of said clutch elements having a portion adapted to be attracted by said electro-magnet upon energization thereof to drivingly engage said driving and driven clutch elements, spring means yieldably urging said driving and driven elements toward disengaged position, means actuated by said driven element for imparting motion of said driven element to the associated picker means, and electrical control means operated by said loom for selectively energizing and deenergizing the electro-magnet in one or the other of said actuating mechanisms during each pick cycle of the loom, said electrical control means including means operable while said loom is in operation for independently varying the times in each pick cycle at which the selected electro-magnet is energized and deenergized.

7. In a picking mechanism for looms having picker means at each end thereof, actuating mechanism for each picker means comprising a rotatable driving clutch element, means for rotating said driving clutch element, a driven clutch element, one of said clutch elements including an electro-magnet and the other of said clutch elements having a portion adapted to be attracted by said electro-magnet upon energization thereof to drivingly engage said driving and driven clutch elements, spring means yieldably urging said driving and driven elements toward disengaged position, means actuated by said driven element for imparting motion of said driven element to the associated picker means, switch means operated by said loom for energizing one or the other of the electro-magnets in said actuating mechanisms during each pick cycle of the loom for initiating of movement of the associated picker means, switch means operated by the affected driven clutch element for deenergizing the affected electro-magnet, and means operable while said loom is in operation to independently vary the times at which each of said switch means is effective.

8. In a picking mechanism for looms having picker means at each end thereof, actuating mechanism for each picker means comprising a flywheel, means for rotating said flywheel, a driving clutch element fixed for rotation with said flywheel, said driving clutch element including an electro-magnet, a driven clutch element, said driven clutch element having a portion adapted to be attracted by said electro-magnet upon energization thereof to drivingly engage said driving and driven clutch elements, spring means yieldably urging said driving and driven elements toward disengaged position, means actuated by said driven element for imparting motion of said driven element to the associated picker means, switch means operated by said loom for energizing one or the other of the electro-magnets in said actuating mechanisms during each pick cycle of the loom for initiation of movement of the associated picker means, switch means operated by the affected driven clutch element for deenergizing the affected electro-magnet, and means operable while said loom is in operation to independently vary the times at which each of said switch means is effective.

9. In a picking mechanism for looms having picker means at each end thereof, actuating mechanism for each picker means comprising a rotatable driving clutch element, means for rotating said driving clutch element, a driven clutch element, means for causing relative move-

ment between said driving clutch element and said driven clutch element to bring said elements into frictional engagement, spring means yieldably urging said driving and driven elements toward disengaged position, means actuated by said driven element for imparting motion of said driven element to the associated picker means, means operated by said loom for moving said clutch elements into and out of frictional engagement, and means operable while said loom is in operation for varying the amount of energy imparted to either of said picker means by the associated actuating mechanism, said last-named means including means for varying the amount of slippage between said frictionally engaged clutch elements.

10. In a picking mechanism for looms having picker means at each end thereof, actuating mechanism for picker means comprising a rotatable driving clutch element, means for rotating said driving clutch element, a driven clutch element, an electro-magnet for causing relative movement between said driving clutch element and said driven clutch element to bring said elements into frictional engagement, spring means yieldably urging said driving and driven elements toward disengaged position, means actuated by said driven element for imparting motion of said driven element to the associated picker means, means operated by said loom for energizing and deenergizing said electro-magnet, and means operable while said loom is in operation for varying the amount of energy imparted to either of said picker means by the associated actuating mechanism, said last named means including means for varying the effective strength of the affected electro-magnet whereby differing amounts of slippage will occur between said frictionally engaged clutch elements.

11. In a picking mechanism for looms having picker means at each end thereof, actuating mechanism for each picker means comprising a rotatable driving clutch element, a driven clutch element, one of said clutch elements including an electro-magnet and the other of said clutch elements having a portion adapted to be attracted by said electro-magnet upon energization thereof to frictionally engage said driving and driven clutch elements, spring means yieldably urging said driving and driven elements toward disengaged position, means actuated by said driven element for imparting motion of said driven element to the associated picker means, switch means operated by said loom for energizing one or the other of the electro-magnets in said actuating mechanism during each pick cycle of the loom for initiating of movement of the associated picker means, and means operable while said loom is in operation for adjusting the effective strength of either of said electro-magnets whereby to vary the amount of energy imparted to said picker means.

12. In a picking mechanism for looms having picker means at each end thereof, actuating mechanism for each picker means comprising a rotatable driving clutch element, a driven clutch element, one of said clutch elements including an electro-magnet and the other of said clutch elements having a portion adapted to be attracted by said electro-magnet upon energization thereof to frictionally engage said driving and driven clutch elements, spring means yieldably urging said driving and driven elements toward disengaged position, means actuated by said driven element for imparting motion of said driven element to the associated picker means, switch means operated by said loom for energizing one or the other of the electro-magnets in said actuating mechanism during each pick cycle of the loom for initiating of movement of the associated picker means, and means automatically operable by said loom for changing the effective strength of at least one of said electro-magnets for predetermined pick cycles of the loom whereby the amount of energy imparted to the associated picker means in said prede-

terminated pick cycles is different from the amount of energy imparted thereto in the remaining pick cycles.

13. In a picking mechanism for looms having picker means at each end thereof, actuating mechanism for each picker means comprising a rotatable driving clutch element, means for rotating said driving clutch element, a driven clutch element, one of said clutch elements including an electro-magnet and the other of said clutch elements having a portion adapted to be attracted by said electro-magnet upon energization thereof to frictionally engage said driving and driven clutch elements, spring means yieldably urging said driving and driven elements toward disengaged position, means actuated by said driven element for imparting motion of said driven element to the associated picker means, switch means operated by said loom for energizing one or the other of the electro-magnets in said actuating mechanism during each pick cycle of the loom for initiating of movement of the associated picker means, means operable while said loom is in operation for adjusting the effective strength of either of said electro-magnets whereby to vary the amount of energy imparted to said picker means, and means automatically operable by said loom for changing the effective strength of at least one of said electro-magnets for predetermined pick cycles of the loom whereby the amount of energy imparted to the associated picker means in said predetermined pick cycles is different from the amount of energy imparted thereto in the remaining pick cycles.

14. In a picking mechanism for looms having picker means at each end thereof, actuating mechanism for each picker means comprising a rotatable driving clutch element, means for rotating said driving clutch element, a driven clutch element, one of said clutch elements including an electro-magnet and the other of said clutch elements having a portion adapted to be attracted by said electro-magnet upon energization thereof to frictionally engage said driving and driven clutch elements, spring means yieldably urging said driving and driven elements toward disengaged position, means actuated by said driven element for imparting motion of said driven element to the associated picker means, switch means operated by said loom for energizing one or the other of the electro-magnets in said actuating mechanism during each pick cycle of the loom for initiating of movement of the associated picker means, switch means operated by the affected driven clutch element for deenergizing the affected electro-magnet, means operable while said loom is in operation to independently vary the times at which

each of said switch means is effective to vary the timing and duration of stroke of the associated picker means, and means operable while said loom is in operation to adjust the effective strength of either of said electro-magnets to vary the amount of energy imparted to the associated picker means.

15. In a picking mechanism for looms having picker means at each end thereof, actuating mechanism for each picker means comprising a rotatable driving clutch element, means for rotating said driving clutch element, a driven clutch element, one of said clutch elements including an electro-magnet and the other of said clutch elements having a portion adapted to be attracted by said electro-magnet upon energization thereof to frictionally engage said driving and driven clutch elements, spring means yieldably urging said driving and driven elements toward disengaged position, means actuated by said driven element for imparting motion of said driven element to the associated picker means, switch means operated by said loom for energizing one or the other of the electro-magnets in said actuating mechanism during each pick cycle of the loom for initiating of movement of the associated picker means, switch means operated by the affected driven clutch element for deenergizing the affected electro-magnet, means operable while said loom is in operation to independently vary the times at which each of said switch means is effective to vary the timing and duration of stroke of the associated picker means, means operable while said loom is in operation to adjust the effective strength of either of said electro-magnets to vary the amount of energy imparted to the associated picker means, and means operated automatically by said loom for changing the effective strength of at least one of said electro-magnets for predetermined pick cycles of said loom whereby the amount of energy imparted to the associated picker means in said predetermined pick cycles is different from the amount of energy imparted thereto in the remaining pick cycles.
